UNITED STATES PATENT OFFICE.

ROLAND BAXTER TAYLOR AND LUCINDA TAYLOR, OF MELVILLE, SASKATCHEWAN,
CANADA.

FOLDER FOR PRESCRIPTION BLANKS.

1,423,473.

Specification of Letters Patent. Patented July 18, 1922.

Application filed May 19, 1921. Serial No. 471,001.

To all whom it may concern:

Be it known that we, ROLAND BAXTER TAYLOR and LUCINDA TAYLOR, citizens of Canada, and residents of Melville, Province 5 of Saskatchewan, and Dominion of Canada, have invented a new and Improved Folder for Prescription Blanks, of which the following is a description.

Our invention while useful for filing sheets 10 generally is more particularly intended for the filing of prescription blanks.

The general object of the invention is to provide a device of the indicated character having novel securing means for the sheets 15 so arranged that a large number of sheets can be secured in a small space and compact form as well as in a manner that all the sheets may be identified by its number, page, or the like.

20 A further object of the invention is to provide for the filing of the sheets with facility and the holding of the same securely.

Reference is to be had to the accompanying drawing forming a part of this specification, it being understood that the drawing 25 is merely illustrative of examples of the invention.

Figure 1 is a plan view of a filing device embodying our invention;

30 Figure 2 is a cross section on the line 2-2, Figure 1;

Figure 3 is a plan view of one of the securing strips partly completed;

Figure 4 is a fragmentary view of the opposite face of the strip as shown in Figure 1;

Figure 5 is an enlarged cross section 35 through the finished strip;

Figure 6 is a plan view with the securing strips disposed parallel with the hinge of the 40 covers instead of at right angles thereto;

Figure 7 is a perspective view of a filing case advantageously employed to hold the folders.

Our novel sheet-securing means is in practice embodied in a folder comprising covers 45 10 with an intermediate strip 10^a constituting the back of the folder and hingedly secured to top covers, so that either cover may be folded under the other to permit the complete device to lie substantially flat.

On one or both covers we provide elongated securing strips 11. Each strip is provided with parallel slits 12, thereby producing sheet holding tabs 13, the ends 13^a of the 55 tabs being turned under by folding the tabs

along the transverse score line 14, thereby giving the strip a minimum width until the folded ends 13^a are brought outward. The tabs in practice are preferably provided with an adhesive substance so that the tabs may 60 be applied to a sheet A simply by moistening.

A series of the strips are provided and these are arranged in stepped form each being mounted on a base strip 15. The several 65 base strips 15 are successively of less width from the bottom strip to the top one so that the edge portion of the strip projecting beyond the one above has supplied to it its securing strip 11. By the described arrangement the maximum number of prescription blanks or other sheets may be accommodated 70 in the folder of a minimum total thickness.

The sheets are secured to two separated tongues so that a sheet may be securely held 75 near the top and bottom.

The successive sheets are secured to successively lower tabs so that the sheets overlap in vertical series for exposing their numbers, pages, or symbols, given the sheets to 80 identify individual sheets. Also, by reason of the stepped arrangement of the strips 11 the respective series of sheets will overlap laterally so that the edge portion and identifying symbols of one series will appear 85 beyond the next series above.

The overlapping of the sheets in a series obviously produces the total thickness of the assembled sheets at the central portion of the folder and in order to compensate for 90 this increased thickness, we form each strip 11 of a greater thickness at the center and of less thickness toward the ends for which purpose use is made of filling strips 16, 16^a, 16^b, 16^c in any desired number, said filling strips increasing in length from top to bottom of the series as clearly shown in Figure 3. The material forming the strip 11 has a width to be wrapped about the filling strips as shown in the cross section, Figure 5. 100

In Figure 6 we have shown strips 11^a secured parallel with the hinge 10^c of the covers 10^b instead of at right angles as in Figures 1 and 2. The strips are identical with those described being formed with slits 105 12^a and tabs 13^b corresponding in all respects with the slits and tabs of the first-described construction.

The filing case A in which the folders are placed, has an open front a, and on the side 110

a rack B to hold a moistener and pen as well as curved keepers C to hold bottles of moistening water or other material. The case is provided with a raised false bottom 5 D with tapering edges. At the top of the open front a is a strip E rising above the top surface of the case. In practice, one of the folders is maintained on top of the filing case A readily accessible for the pasting in 10 of prescription blanks or the like and as usual with filing systems, folders in given number are employed in the case A and as new folders are added the oldest one is removed and placed in the transfer case. 15 We would state in conclusion that while the illustrated example constitutes a practical embodiment of our invention, we do not limit ourselves strictly to the mechanical details herein illustrated, since manifestly the 20 same can be considerably varied without departure from the spirit of the invention, as defined in the appended claims.

Having thus described our invention, we claim:

1. In a device of the class described, a 25 series of strips of varying widths superimposed in stepped form, each strip presenting a longitudinal series of tabs adapted to be secured to the sheets to be held.
2. In a device of the class described, a 30 sheet-securing strip having tabs along an edge thereof adapted to be applied to the sheets to be secured, said strip being thickest at its central portion and decreasing in thickness toward its ends. 35
3. In a device of the class described, a sheet-securing strip having tabs along an edge thereof adapted to be applied to sheets to be secured, and filling strips enfolded in the material of the first strip and of gradually increasing length. 40

ROLAND BAXTER TAYLOR.
LUCINDA TAYLOR.
